CIGARETTE TURNING DEVICE

Dino Antonelli, Richmond, Va., assignor to American Machine & Foundry Company, a corporation of New Jersey

Application December 30, 1955, Serial No. 556,552

13 Claims. (Cl. 198—32)

This invention relates to cigarette making, and more particularly to a device and method for turning cigarettes received by a collector in a cigarette machine so as to cause the tip ends of all cigarettes to face in the same direction.

In the process of manufacturing filter tip cigarettes and cork tip cigarettes, the cut tipped cigarettes are discharged in two rows onto a collector belt. Due to the method of manufacturing and cutting that is employed in making such cigarettes, the tip ends of the cigarettes in each row face in opposite directions. The cigarettes in one row then have to be turned so that the tip ends of these cigarettes will face in the same direction as the tip ends of the cigarettes of the other row, before the tip cigarettes are transferred in suitable containers to a cigarette wrapping machine.

Various mechanical devices have been devised for turning cigarettes. Some of these devices have been found expensive to construct while others handle the cigarettes so roughly that the cigarettes have undesirable indentations formed thereon by the turning device.

It is an object to provide a simple device which will turn tipped cigarettes facing in one direction to face in another direction which does not have any impacting elements contacting the cigarettes.

A further object of this invention is to provide a cigarette turning device which will avoid having the cigarette contact any impacting element to effect a turning of the cigarette.

A further object is to provide a simple and reliable device for turning tipped cigarettes so that the tip ends will be facing in the direction desired.

Other objects and features of the invention will appear as the description of the particular physical embodiment selected to illustrate the invention progresses. In the accompanying drawings, which form a part of this specification, like characters of reference have been applied to corresponding parts throughout the several views which make up the drawings.

Fig. 1 is an isometric view of the cigarette turner.

Fig. 2 is an end view of the cigarette turner.

Fig. 3 is a side view of the cigarette turner.

Fig. 4 is a top view of the cigarette turner.

Fig. 5 is a modified form of my invention shown in a rotary member for causing cigarettes to be turned end-for-end.

Fig. 6 is a detailed side elevation of the turning wheel structure shown in Fig. 5.

My apparatus is particularly well suited for use with a cigarette machine making either filter tipped cigarettes or cork tipped cigarettes wherein the cut, tipped cigarette lengths are discharged laterally in the manner shown in co-pending application Serial No. 509,293 filed by George Dearsley on May 18, 1955, and in U. S. Patent Reissue 19,375 granted November 20, 1934, to W. B. Bronander. The tipped cigarettes so discharged are then advanced by a collecting conveyor belt 10 in two

2

rows wherein the tipped ends of one row of cigarettes face in a direction opposite to the direction of the other row of tipped cigarettes. In using the term "tipped cigarettes" it is intended to include within its meaning either cork tipped, filter tipped, or hollow mouthpiece cigarettes, any of which may be readily used with this invention.

As these tipped cigarettes are forwarded in the direction indicated by the arrow on collector belt 10, in Fig. 1, they are deposited onto an inclined platform 12 where the cigarettes roll downwardly until the tip ends thereof engage with the abutment 14. Their engagement with this abutment 14 retards the two adjoining ends of the cigarette engaging therewith, while the opposite ends of these cigarettes are free to slide down the chutes 16 and 18.

By the time these opposite ends of the cigarette slide down the chutes 16 and 18 they will have been turned around 90 degrees, whereupon the retarded end of the cigarette is able to fall free of the abutment 14 under the action of gravity. These falling cigarettes, falling downwardly through cut-out sections 15 and 17 are deposited on the transverse collecting belt 25 which travels in the direction indicated by the arrow.

The sides of the collecting belt may be enclosed by suitable side walls 20, 22. Since both cigarettes have been turned in opposite directions, all the cigarettes will be lined up with their tipped ends facing in the same direction on the second collecting belt 25. The second collecting belt, traveling over a suitable pulley 24, advances the cigarettes to a collecting tray where they are stacked manually or automatically.

In the modified form of my invention shown in Fig. 5, I have illustrated a rotary member 26 engaging with the ends of the cigarettes facing each other to assist in effecting a quick 90 degree turn-around of the tipped cigarette as the opposite ends slide down the inclined guideways 28 and 30 so that when the cigarette is ready to fall over the edges 32 and 34 they will have been turned around 90 degrees. The cigarettes so turned around are collected on the conveyor 25 with the tip ends all facing in the same direction in a single row.

While I have shown in the drawings a single retarding element engaging with the tipped ends facing each other of each row of cigarettes, it will be appreciated that a pair of abutting elements could be employed engaging the opposite ends of the cigarettes in each row in lieu of a single abutting element. In this case, the cut out portions of the declining plates would be formed adjacent each abutting element.

Similarly instead of using a pair of declining plates 16 and 18, a single declining plate could likewise be employed with cut out portions formed adjacent each abutting element.

It will also be noted from the foregoing description that no impacting parts are employed in this cigarette turning device which strike the cigarette, so that no undesirable indentations are impressed on the cut cigarette length. Due to the simplicity of the foregoing turning apparatus, it is economical to construct, and yet reliable in operation because of the lack of impacting elements which can malfunction.

The invention hereinabove described may be varied in construction within the scope of the claims, for the particular device selected to illustrate the invention is but one of many possible embodiments of the same. The invention, therefore, is not to be restricted to the precise details of the structure shown and described.

What is claimed is:

1. A device for turning tipped cigarettes so that all the tip ends will face in the direction desired comprising a conveyor for delivering two rows of cigarettes having

the tip ends of the cigarettes in each row facing in opposite directions, to a cigarette turning station, an abutment positioned to be engaged by one of the ends of the cigarettes in each row and be retarded thereby, an inclined chute for directing and allowing the opposite ends of each cigarette to slide down the chute, and in so doing simultaneously effect the turning of each cigarette in each row in opposite directions to effect the turning of the cigarette to the desired direction.

2. A cigarette turning device comprising a conveyor for supporting and advancing two rows of cigarettes wherein the tipped ends of the cigarettes in each row face in opposite directions, an abutment positioned at the middle of the discharge end of said conveyor to engage that portion of the cigarettes of each row which immediately face each other, chutes provided at the discharge end of each row of cigarettes to allow the opposite ends of said cigarettes to slide down the chute to thereby effect a 90 degree turning of said cigarettes as it slides down the chute freeing itself from the abutment.

3. A cigarette turning device comprising a conveyor for moving two rows of tipped cigarettes along a predetermined path wherein the cigarettes of each row have the tipped ends thereof facing in opposite directions, an abutment positioned in the path of the ends of the cigarette of each row which face each other, an inclined chute positioned at the end of said conveyor for causing the opposite ends of said cigarette of each row to slide down and in so doing effect a 90 degree turn of the cigarette, and a collecting conveyor positioned under said inclined chute for receiving the cigarettes which have been turned in this way so that all of the tipped ends are facing in the same direction on the collecting conveyor.

4. A cigarette turning device comprising a collecting belt for receiving and advancing two rows of tipped cigarettes laterally wherein the cigarettes of each row have the tips thereof facing in the same direction, stationary means for retarding the ends of the cigarette facing each other while allowing the opposite ends to continue their forward movement, thereby causing the cigarettes to pivot so that the axis of the cigarette will be substantially transverse to its axis before engaging with said stationary means, and a collecting conveyor onto which said cigarettes drop when they have been turned 90 degrees so as to advance said collected cigarettes sidewise with all of the tips facing in the same direction.

5. A cigarette turning device comprising a conveyor for advancing two adjacent rows of cigarettes laterally wherein the cigarettes in said rows have the tip ends thereof facing in opposite directions, stop means for engaging the same ends of the cigarettes so as to retard these ends while allowing the opposite ends of the cigarettes to continue movement, means for facilitating the movement of the opposite ends of the cigarettes to cause the cigarettes so engaged to turn 90 degrees, and a common collecting member for receiving the cigarettes after they have been so turned and supporting the same so that all of the tip ends face in the same direction.

6. A cigarette turning device for successively turning tipped cigarettes in two rows so that all of the cigarettes will have their tip ends facing in the same direction comprising means for forwarding cigarettes in each of said rows successively to a turning station, pivot means positioned to be engaged by one end of the cigarette to hold it substantially stationary, means provided for causing the free end of the cigarette to be pivoted around the retarded end and means for collecting said turned around cigarettes when the tipped ends of said cigarettes have been caused to face in the same direction.

7. A cigarette turning device comprising a conveyor belt for receiving pairs of cigarettes in two rows wherein the tip ends of the cigarettes in each row face in opposite directions, a pair of inclined chutes along which cigarettes can slide downwardly, a stop positioned to engage

one end of the cigarettes of each of said rows while allowing the opposite ends of the cigarettes so engaged to slide downwardly on said chute to thereby cause the cigarettes to be turned so that all the tip ends face in the same direction, said chutes having cut away portions allowing the cigarettes to fall downwardly by the force of gravity after they have been turned by sliding down said chute a predetermined distance, to thereby collect said cigarettes on a second collecting belt, so that all the tip ends face in the same direction.

8. A cigarette turning device comprising a conveyor for delivering two rows of cigarettes having the cigarettes of each row facing in the opposite direction to a turning station, means for detaining one end of the cigarettes of each row against movement while allowing the opposite end of each detained cigarette to pivot about the detained end of the cigarette, means for allowing the detained end of said cigarette to fall free from said detaining means when the cigarette has been turned a predetermined distance, and a collecting conveyor for receiving said detained cigarettes when they have become disengaged from said detaining means to accumulate said detained cigarettes so that the tipped ends all face in the same direction.

9. A device for turning cigarettes comprising a conveyor belt for advancing two rows of cigarettes to a turning station, means for temporarily restraining one end of the cigarette of each row while allowing the other end to pivot about the restrained end, means allowing said cigarettes to fall downwardly when they have moved a predetermined distance around said pivot, and a collecting conveyor for receiving said cigarettes when they fall so that all of said collected cigarettes will have the tip ends facing in the same direction.

10. A cigarette turning device comprising a pair of declining plates having a cut out portion formed therebetween through which turned tipped cigarettes can drop, a collecting belt for receiving turned cigarettes falling through said cut out portion in side by side relationship, means for delivering tipped cigarette lengths arranged side by side in rows so that the tip ends of the cigarettes in each row face in opposite directions to said declining plates, means positioned in the path of each of said rows of cigarettes to engage with one end of the cigarettes in each row to retard the ends so engaged temporarily while allowing the other end of each of said cigarettes to slide down said declining plates, thereby causing the cigarettes to be turned 90 degrees before falling through said cut out portion, and a collector for receiving said turned cigarettes in side by side relationship with all of the tip ends facing in the same direction.

11. A cigarette turning device comprising a conveyor mechanism for advancing two rows of cigarettes having the cigarettes in each row transversely arranged with respect to their direction of movement and wherein the tip ends of the cigarettes in each row face in opposite directions, a declining plate for receiving cigarettes from said mechanism, said plate having a cut out opening through which cigarettes discharged therethrough can fall, means positioned in the path of travel of said cigarettes to engage with one end of the cigarettes in each row to cause said end to be temporarily restrained while enabling the opposite end of each restrained cigarette to slide down over said declining plate to pivot about said restraining means so as to cause the cigarette to turn 90 degrees before falling through said cut out opening, a collector positioned under said cut out opening to collect cigarettes falling therethrough in side by side relationship wherein all tipped ends of the cigarettes face in the same direction.

12. A cigarette turning device comprising a conveyor, a pair of declining plates connecting with the delivery end of said conveyor belt for receiving transversely arranged cigarettes discharged from said conveyor belt, a

restraining device engaging with one end of the cigarettes in each row to temporarily restrain movement of that end of the cigarette to cause the cigarette to pivot about said device when sliding down said declining plate to cause the axial length of the cigarettes to be turned approximately 90 degrees before falling through said cut out opening, a cigarette collector under said cut out opening to receive cigarettes in side by side arrangement falling through said cut out opening so that all of the cigarettes will be collected side by side with their tip ends all facing in the same direction.

13. A cigarette turning device comprising a source of cigarettes arranged side by side in row formation which are advanced in a direction transverse to their axial lengths, means positioned to engage with the ends of the cigarettes in each row as they are advanced from said source, a pair of declining plates positioned adjacent said means and having a cut out portion formed adja-

cent said means through which cigarettes can drop, said means acting to engage and temporarily hold back one end of the cigarettes in each row as they come in contact with said means, while causing the other end of the cigarette to pivot about the means engaging with the ends of said cigarette to cause the cigarettes to turn 90 degrees as they slide down the declining plate before dropping through said cut out portion, a cigarette collector positioned underneath said cut out portion for receiving cigarettes in side by side relationship with all of the tipped cigarettes facing in the same direction.
